(57) CLAIM

The ornamental design for a coldwater dogdish, as shown and described.

DESCRIPTION

FIG. 1 is a top perspective view of a coldwater dogdish showing my new design;

FIG. 2 is a left-side elevational view thereof;

FIG. 3 is a front elevational view thereof;

FIG. 4 is a rear elevational view thereof;

FIG. 5 is a top plan view thereof; and,

FIG. 6 is a bottom plan view thereof.

The broken lines shown in FIG. 1 are for illustrative purposes only and form no part of the claimed design.
